CLAIM

The ornamental design for a caller ID display device without a variable extending stand, as shown and described.

DESCRIPTION

FIG. 1 is a front-right side perspective view of a caller ID display device.

FIG. 2 is a left side view of the caller ID device of FIG. 1.

FIG. 3 is a right side view of the caller ID device of FIG. 1.

FIG. 4 is a top view of the caller ID device of FIG. 1.

FIG. 5 is a bottom view of the caller ID device of FIG. 1.

FIG. 6 is a front view of the caller ID device of FIG. 1; and,

FIG. 7 is a rear view of the caller ID device of FIG. 1.

The features shown at the rear, FIG. 7, by means of broken lines, form no part of the claimed design.
